UNITED STATES PATENT OFFICE.

HENRY A. LIEFER, OF SAND CREEK TOWNSHIP, SCOTT COUNTY, MINNESOTA.

BUNDLE TIE.

Application filed November 8, 1923. Serial No. 673,590.

To all whom it may concern:

Be it known that I, HENRY AUGUST LIEFER, a citizen of the United States, residing at Sand Creek Township, in the county of Scott and State of Minnesota, have invented 5 certain new and useful Improvements in Bundle Ties; and I do declare the following to be a full, clear, and exact description of the invention, such as will enable others 10 skilled in the art to which it appertains to make and use the same.

My invention relates to improvements in bundle ties of the type formed of bent wire, and while the device is usable also for other 15 purposes, its primary use is in connection with the twine used for tying shocks and bundles of corn.

I am aware that numerous bundle ties 20 formed of wire, have been heretofore provided, but it is the object of my invention to provide an exceptionally simple and inexpensive device which may be operated with extreme ease and which will so effectively anchor the free end of the twine, as to make 25 it impossible to release it by pulling.

With the foregoing in view, the invention resides in the novel subject matter herein-after described and claimed, the description being supplemented by the accompanying 30 drawing.

Figure 1 is a plan view of the improved bundle tie, showing the first step in anchoring the free end of a cord thereby.

Figure 2 is an edge elevation showing the 35 position of the cord in the tie at the completion of the first operation.

Figure 3 is a perspective view showing the next operation of anchoring the cord.

Figure 4 is a perspective view showing the 40 cord completely anchored.

The improved tie is formed of a single length of wire 1, one end of said wire being suitably bent to provide an eye or other means 2 for connecting it with one end of a 45 cord 3. The other end of the wire 1 is bent to form a coil having one complete convolution 4 and a second incomplete convolution 5, the two convolutions being of uniform diameter. The body portion of the 50 wire is substantially tangential to the convolution 4 and forms therewith an acute entrance throat 6, and the free end of the incomplete convolution 5 terminates in a short finger 7 extending obliquely outward from

the plane of this convolution, providing a 55 second acute entrance throat 8 between itself and the adjacent portion of the convolution 4.

In operating the device, one end of the cord 3 is attached to the eye or the like 2, 60 and the cord is then passed around the bundle to be bound. The cord is guided into the throat 6 as shown in Fig. 1 and when it is pulled, it moves between the convolutions 4 and 5 and extends through the former, away 65 from the convolution 5, as seen in Fig. 2. The cord is then passed outwardly around the outer sides of both convolutions as indicated in Fig. 3, and is guided into the throat 8. Then, by pulling upon the cord, it may 70 be slid into tight relation with the portions previously engaged with the coil. When engaged with the tie in the manner described, the cord is in effect wrapped about one side of the convolutions 4 and 5 and is 75 passed between these convolutions adjacent the wrapping. Thus, when a pull is placed upon the bundle-encircling portion of the cord, the portion 9 of this cord which extends around the outer sides of the convolutions 4 and 5, pulls these convolutions toward each other and tightly clamps the cord at two points, so that it is an impossibility to 80 slip the cord from the tie, without first moving the free end of the cord through the 85 throat 8. It will thus be seen that the device is much more effective than similar bundle ties heretofore devised. Furthermore, 90 it is more simple and consequently less expensive.

As excellent results are obtainable from the details disclosed, these exact details are preferably followed, but within the scope of the invention as claimed, minor changes may 95 be made.

I claim:

A bundle tie comprising a length of wire adapted at one end for connection to one end of a cord, the other end of said wire being coiled to form one complete convolution and one incomplete convolution of uniform diameter, the body portion of the wire being substantially tangential to the outer end of said complete convolution and forming therewith an acute unobstructed entrance throat into which the free end of the cord is pulled to position said cord between the two convolutions with its free end ex- 100 105 110 115

tending through said complete convolution away from said incomplete convolution, the free end of said incomplete convolution terminating in a short finger projecting outwardly away from the plane of such convolution and providing a second acute entrance throat into which the cord is pulled after

first passing the cord through the first named throat and then passing it outwardly around both convolutions.

10

In testimony whereof I have hereunto affixed my signature.

HENRY A. LIEFER.
